[57] **CLAIM**

The ornamental design for a floor standing loudspeaker, as shown and described.

DESCRIPTION

FIG. 1 is a front elevational view of a floor standing loudspeaker, showing my new design, the rear thereof being void of ornamentation;

FIG. 2 is a right side elevational view thereof, the left side being a mirror image thereof;

FIG. 3 is a top plan view thereof;

FIG. 4 is a bottom plan view thereof; and,

FIG. 5 is a top, front and left-side perspective view thereof.
